UNITED STATES PATENT OFFICE

2,062,291

TUBE FORMING MACHINE

Herbert S. Brown, Chicago, Ill.

Application August 31, 1934, Serial No. 742,227

12 Claims.

(Cl. 93—80)

This invention relates to a machine for making spiral tubes, and concerns itself primarily with the means for forming the tubes.

In the past, it has been the common practice to wind strips of fibrous material, such as paper or the like, around a mandrel by means of a belt. It has been found in practice that a belt stretches very quickly in use, and that it is difficult to maintain a positive and constant tension on the tube being wrapped. Due to the stretching of the belt in use, it is impossible to obtain a uniform tension on a belt drive.

It is an object of this invention to overcome the above noted objections to a belt drive in the use of a rubber roller or the like that can be readily adjusted for obtaining the desired tension, which will also be uniform. Further, the roller will have a better ironing effect upon the tube and will increase the output of such tubes in addition to the production of a better product.

The invention comprises the novel structure and combination of parts hereinafter described and more particularly pointed out and defined in the appended claims.

In the accompanying drawings which illustrate a preferred form of this invention, and in which similar reference numerals refer to similar features in the different views:

Figure 1 is a side elevational view of a tube forming machine involving this invention.

Figure 2 is a view taken substantially upon the line II—II of Figure 1 looking in the direction of the arrows and showing parts in section.

Figure 3 is a sectional view taken upon the line III—III of Figure 2, showing the operating parts in elevation.

Figure 4 is an enlarged sectional view taken substantially upon the line IV—IV of Figure 2, showing in dotted lines the operation of parts.

Figure 5 is an enlarged sectional view taken upon the line V—V of Figure 1.

Figure 6 is an enlarged plan view of the tube forming means and the paper guide leading thereto, with parts of the machine omitted, and taken substantially upon the line VI—VI of Figure 1, looking in the direction of the arrows.

Figure 7 is an enlarged sectional view through a tube showing parts of the forming means in elevation.

Figure 8 is an enlarged longitudinal sectional view through the stationary mandrel, showing the cutting knives held in inoperative positions.

Figure 9 is a view similar to Figure 8, showing the cutting knives in operative positions.

Figure 10 is an enlarged sectional view taken

upon the line X—X of Figure 8, looking in the direction of the arrows.

Figure 11 is an enlarged sectional view taken upon the line XI—XI of Figure 9 looking in the direction of the arrows.

Figure 12 is an enlarged fragmentary vertical sectional view of the cutting head shown at the extreme right in Figure 9.

Figure 13 shows a section of a tube formed in the machine.

As an exemplification of this invention, there is shown in the drawings a supporting base 1 which may be similar to the base of a milling machine, having a table or platform 2 thereon, which may be adjusted in its plane by means of a screw 3 and which may be vertically adjusted by means of a screw 4.

A support 5 rises from the platform 2 and this support sustains a bearing 6 in which a metal mandrel 7 shown in section in Figures 8 and 9 is supported for longitudinal adjustment. At the rear of the base 1, there is an upright wall 8 from which there extends a horizontal arm or support 9. This arm 9 carries a bearing 10 which in turn has an integral arm 11 terminating in a bearing 12 in which the outer end of a roll shaft 13 is journaled. The shaft 13 carries a roller 14 having a yielding periphery secured thereon. This roller may be formed of any suitable material, such as solid rubber, for example, which is the preferable material from which the present roller is made. With reference to Figures 1 and 6, it will be observed that the mandrel 7 is obliquely arranged with respect to the roll shaft 13, for the purpose of rolling the paper web in spiral form.

The interior of the tube is formed from a strip of paper 15 unwound from a reel 16 and passing through a dust remover 17 which may consist of two confronting brushes 17a. The strip of paper then passes through a glue applying box 18 in which a glue applying roll 19 is mounted. The rolls 20 act as guide rolls to direct the strip of paper against the glue applying rolls. The rolls 21 and 22 guide the strip 15 with the glue applied to its bottom surface from the glue box 18 to a feed roll 23. Between the glue box 18 and the feed roll 23, there is a waxing pad 24 for waxing the upper surface of the strip 15. This waxed surface forms the interior surface of the tube. From the roll 23, the glued and waxed strip 15 passes through a guide-way 25 (Fig. 5) formed in a guide block 26 suitably supported adjacent said roll 23 and extending to a point adjacent the mandrel 7. Upon the top of the guide block 26, there is a hinge plate 27 that has a fillet 28.

extending into the guide-way 25 and forming the top thereof. A second guide block 29 is hinged to the top of the plate 27 and this second guide block has a guide groove 30 in its bottom that overlaps one-half of the guide groove 25. The top of the plate 27 is also preferably provided with a shallow guide groove 31 that registers with the guide groove 30. The grooves 30 and 31 form a guide-way for a strip of paper 32 which is fed over a guide roll 23* above the roll 23 from a reel 34 located above the reel 16. The dirt and dust upon the strip of paper 32 are also removed when the same passes through a brushing device 17 similar to the dust removing device 15 for the strip 18. The rolls 23 and 23* are journalled in a suitable casing 35 attached to a bracket 36 rising from the platform 2.

With reference to Figure 5, it will be noted that the glued and waxed strip 18 is below the strip 32 and overlapped thereby. The strips emerge from the guide-ways in overlapping relation as shown in Figure 6, with the glued face of the strip 18 uppermost.

It might be here mentioned that the strips are placed in their respective guideways in the following manner: The block 29 is first swung back, then the plate 27 is swung back, and the strip 18 is then inserted in its guideway; the plate 27 is swung to its guide-way closing position, then the strip 32 is inserted in the guide groove of plate 27 and the block 29 is swung thereover. After the two strips have been placed in their respective guide-ways, they are adapted to be manually wound around the mandrel 7 before starting the machine. However, before the strips can be manually wound around the mandrel to a point under the roller, it might be necessary to lower the platform 2 and mandrel 7 by the screw 4. Before starting the machine, the mandrel will of course be raised for obtaining the proper pressure against the roller. When the machine is started the roller 14 will engage the strips on the mandrel and cause the same to rotate in a spiral direction around the mandrel, 45 and after a predetermined number of revolutions, a certain cutting mechanism will come into action for shearing a suitable length from the tube.

The shearing mechanism is best illustrated in Figs. 9 to 12, and in referring to these figures, it will be observed that the cutting mechanism comprises a circular series of centrifugally actuated knives 38 pivotally mounted upon the outer side surface of a cylindrical head 34. Each knife 38 has a straight edge 38^a, and a curved cutting edge 38^b extending from the straight edge. This curved cutting edge 38^b terminates in a blunt or thickened edge a short distance from the straight edge 38^a. This thickened edge continues rearwardly and merges into a tail portion comprising an elevated shoulder 38^c. The knives 38 are pivoted to the head 34 by means of pivot screws 39 which extend eccentrically through the knives at substantially the point most remote from the straight edge 38^a. Each knife has an aperture 37 located adjacent the shoulder 38^c thereof and adjacent the straight edge 38^a thereof. It will be noted that each shoulder 38^c has an outer curved or arcuate surface 37 facing the aperture 37.

The knife head 34 is secured upon the outer end of a rotatable hollow shaft 38 journalled in suitable bearings 39 and 40 in the ends of the mandrel. The bearing 40 is in the form of a sleeve mounted in a long bearing sleeve 41 within the hollow shaft. The hollow shaft 38 extends

beyond the rear end of the mandrel 7 for carrying a driving pulley 42 secured thereto.

A rod 43 extends through the hollow shaft 38 and through the cutter head 34. Beyond the cutter head, a disk 44 is secured upon the end 5 of the rod 43. The disk 44 has a circular series of pins 45 secured thereon. These pins have their inner portions pointed or bevelled, and they are arranged for engaging the apertures 36 in the centrifugal cutters when said disk is moved 10 toward the left. The rod 43 has a limited longitudinal movement governed by the length of a slot 46 in the shaft 38 into which a pin 47 on the rod 43 extends. The rod 43 must hence rotate with the shaft 38. As it cannot rotate relative to 15 such shaft, the pins 45 will always remain in proper positions.

In Figures 9 and 12, the pins 45 are shown in their inoperative relation with the cutters 38. If the shaft 38 is now rotated, the cutters will 20 move outwardly as shown in Figure 11, for cutting a length from the tube. The outward movement of the cutters is limited by the engagement of the shoulders 38^c with the pins 45. After a length has been sheared from the tube, the disc 25 44 will automatically move to the left and the bevelled pins 45 will engage the apertures in the cutters and swing the same inwardly of the periphery of the disk to the positions shown in Figure 10.

In the event that the apertures 36 in the cutters move too far outwardly and out of register with the pins, the bevelled ends of the pins acting against the shoulders 38^c of the cutters will swing the same inwardly until said pins can pass into 35 the apertures 36. As a general rule, the cutters will first be swung inwardly a limited extent by the movement of the pins against the shoulders 38^c of the cutters before said pins engage the apertures.

The hollow shaft 38 is normally restrained against rotation. It is adapted for slight longitudinal movement in its bearings to engage and disengage a friction collar 48 thereon with respect to a radial flange 49 on the bearing 38. Normally 45 the collar 48 engages the friction flange 49, being yieldingly held thereagainst by means of a coil spring 50 located between the bearing 38 and the pulley 42. When the rod 43 is moved toward the right, the shaft 38 will also move longitudinally 50 a short distance to the right as shown in Figure 9, as will presently appear.

A collar 51 is secured upon the rear end of the rod 43 and a coil spring 52 is positioned between said collar and the outer end of the pulley. A lever 53 engages the rear end of the rod 43 with the result that when said lever 53 is actuated, the spring 52 will be compressed for moving the pulley 42 and shaft 38 toward the right; the spring 50 which is a weaker one, will be compressed as 60 shown in Figure 9. When the rod 43 is in its inoperative position as shown in Figure 8, the hub of the collar is spaced a short distance from the rear end of the shaft 38. However, when the rod 43 is moved to the right to release the cutters, the hub of collar 51 will engage the end of the shaft 38 and limit further relative longitudinal movement thereof. The rod 43 hence has a fixed relative longitudinal movement with respect to shaft 38 whereby the pins will always be properly 70 spaced with respect to the cutters.

The lever 53 is fulcrumed intermediate its ends upon a pivot 55 (Fig. 2) attached to a bracket 56 extending from the wall 6. Extending upwardly from the support 6, there is a bracket 58 support- 75

ing a sprocket wheel 57. The bracket 56 has a lug or ear 58 (Fig. 3) extending from one edge. A lever 59 is pivoted intermediate its ends upon said ear 58. The lower end of this lever carries a block 60 (Fig. 4) having a sloping edge 61 directed toward the upper end of the lever 53. The upper end of the lever 59 has a laterally directed tail portion 62 having a sloping surface adapted to be engaged by a lug 63 on the sprocket wheel 57. The lug 63 has a sloping surface 64 adapted for engaging the sloping tail portion 62 of the lever 59 and shifts the latter as shown in dotted lines in Figure 4, for causing the sloping edge 61 on the block 60 to shift lever 53 as indicated in dotted lines in Figure 4. This shifting of lever 53 will move rod 43 for disengaging the pins from the cutter knives.

As the lug 63 rides off the tail portion 62 of the lever 59, a spring 65 (Fig. 3) which connects the lever 59 with the bracket 56 comes into action for returning such lever to its normal position. From the foregoing, it will be apparent that the cutting knives are released once during each rotation of the sprocket wheel 57 caused by the sprocket chain 66 which is driven by a sprocket wheel 67 secured upon the roll shaft 13.

The shaft 13 is driven by a belt 68 trained over a pulley 69 secured upon the shaft 13 which extends through the wall 8. Suitable bearings 70 and 71 are provided upon the wall 8 for the shaft 13. The belt 68 is driven by a suitable motor 72 (Fig. 1) supported upon the edge of the wall 8.

The cutter shaft 38 is periodically rotated by a belt 73 which is trained over the pulley 42 thereon. The belt 73 is driven by a motor 74 (Fig. 1) secured upon the bottom of the platform and having a slip connection with one of its pulleys when the cutter shaft is frictionally retained.

If desirable, a chain tightening means may be employed in connection with the sprocket chain 66. In the drawings, a small sprocket wheel 75 mounted upon a bracket 76 attached to the bracket 56 is shown as engaging the chain 66 just below the sprocket wheel 57 for such a purpose.

In Figure 13, there is shown a section 77 of a tube formed in this machine. This section, during the operation of the machine, or similar sections are cut from the tube as soon as a sufficient length projects beyond the end of the mandrel 7.

While the operation of the machine should be understood from the foregoing, it is desired to point out that the roller 14 engages the rear portion of the already formed tube on the mandrel as shown in Figure 6 and causes a turning movement thereof. The yielding rubber serves to frictionally engage the tube and cause the same to rotate around the mandrel. The rubber surface of the roll has a high degree of friction in contact with the tube and practically no slipping tendency.

The two strips 15 and 32 are not engaged by the roll as they reach the mandrel, but pass to the mandrel beyond one end of the roller. It will be noted that the unglued strip 32 rolls over the adjacent half of strip 15 to the right and over the adjacent half of strip 15 to the left and is glued over the juncture of the edges of strip 15 as the strips are coiled in a spiral around the mandrel. The roller 14 not only causes the rotation of the tubes around the mandrel, it also irons the strip 32 over adjacent parts of strip 15 and glues the same thereon. It might be mentioned that the platform 2 that carries the mandrel may be vertically adjusted to vary the operative relation between the mandrel and roller to vary the pressure ex-

erted by the roll and to admit the tube forming material between the mandrel and roller.

It will be appreciated that the use of a roller working over a stationary mandrel will exert a positive and constant pressure that may be increased or decreased. It is also possible to speed up the roller and increase the capacity of the machine without any liability of damaging the tube. At the same time, the roller will exercise an ironing effect to produce a smooth tube due to the pressure that is exerted thereby. If the tube is waxed upon the interior, such wax can be pressed into any indentations in the paper and into any crevices occurring between adjacent coils, far more effectively than is possible with the use of a belt.

I am aware that many changes may be made and numerous details of construction may be varied through a wide range without departing from the principles of this invention, and I therefore, do not purpose limiting the patent granted hereon otherwise than is necessitated by the prior art.

I claim as my invention:

1. In a tube forming machine, a vertically adjustable platform, a stationary mandrel supported upon said platform, a vertical member adjacent said platform, an arm extending from said member in oblique relation to said mandrel, a bearing carried by said arm, a shaft journaled in said member and bearing and a roller secured to said shaft for cooperating with said mandrel.

2. In a machine of the class described, a mandrel, a roller cooperating with said mandrel, means including a rotatable member for rotating said roller, a cutter shaft extending through said mandrel, cutting elements carried by said shaft, means for normally restraining said shaft against rotation, and means periodically operated by said rotatable member for shifting said cutter shaft for the purpose set forth.

3. In a machine of the class described, a mandrel, a roller cooperating with said mandrel, driving mechanism for said roller including a rotatable member, a cutter shaft extending through said mandrel, centrifugally actuated cutters carried by said shaft, means for retaining said cutters against centrifugal movement, frictional means for normally retaining said cutter shaft against rotation, a rod extending through said shaft and having means for controlling said cutters, and means periodically actuated by said rotatable member for shifting said rod and shaft for the purpose set forth.

4. In a machine of the class described, a mandrel, a roller cooperating with said mandrel, means for rotating said roller including a rotatable member, a shaft extending through said mandrel, centrifugal cutters mounted upon said shaft beyond the end of said mandrel, means including a rod extending through said shaft for controlling said cutters, means for periodically restraining said shaft against rotation, and means periodically operated by said rotatable member for shifting said rod and shaft for the purpose set forth.

5. In a machine of the class described, a mandrel, a roller cooperating with said mandrel for forming a spiral tube, means for operating said roller including a rotatable member, centrifugal cutters at the end of said mandrel for shearing the tube, a hollow shaft extending through said mandrel and supporting said cutters, a rod extending through said shaft and having means for engaging and shifting said cutters, and means

periodically operated by said rotatable member for controlling said rod and cutter shaft.

6. In a machine of the class described, a mandrel, a roller cooperating with said mandrel for forming a spiral tube, means including a rotatable member for rotating said roller, centrifugal cutters at the end of said mandrel for shearing said tube, means for normally maintaining said cutters inoperative and means periodically operated by said rotatable member for rendering said cutters operative.

7. In a machine of the class described, a mandrel, a roller cooperating with said mandrel, means for rotating said roller including a rotatable member, a shaft extending through said mandrel, cutters at the end of said shaft and means responsive to the rotation of said rotatable member for controlling said cutters.

8. In a machine of the class described, a hollow mandrel, a roller cooperating with said mandrel, a member extending through said mandrel, centrifugal cutters attached to said member at the end of said mandrel, a rod extending through said member and having means for engaging and moving said cutters and maintaining the same in an inoperative position, driving means including a rotatable member for operating said roller and means periodically actuated by said rotatable member for shifting said rod for releasing said cutters.

9. In a machine of the class described, a hollow mandrel, a roller cooperating with said mandrel, a hollow shaft extending through said mandrel, centrifugal cutters pivotally mounted upon said shaft beyond the end of said mandrel, a rod extending through said shaft, a circular series of

pins carried by said rod beyond said cutters, said cutters having holes to receive said pins, yielding means for normally maintaining said rod with said pins in engagement with said holes, means for rotating said roller including a rotatable member and means periodically operated by said rotatable member for shifting said rod for disengaging said pins from said cutters.

10. In a spiral tube forming machine, a horizontal shaft, a roller secured to said shaft, a mandrel extending obliquely to said roller in operative relation therewith, means for adjusting said mandrel to and from said roller, and means for operating said shaft for rotating said roller and winding material on said mandrel.

11. In a tube forming machine, a mandrel, a single roller cooperating with said mandrel for drawing and winding material thereon, a shaft extending coaxially through said mandrel, cutting elements carried by said shaft, driving mechanism for said roller and means including a slideable element extending through said mandrel and responsive to said driving mechanism for controlling said cutters.

12. In a tube forming machine, a mandrel, a single roller cooperating with said mandrel and forming the sole means for winding material upon said mandrel, means for operating said roller including a rotatable member, cutting mechanism at the end of said mandrel for severing tubes, a slideable element extending through said mandrel for controlling said cutting mechanism and means responsive to said rotatable member for moving said slideable element in one direction.

HERBERT S. BROWN.
